(57) **CLAIM**

We claim the ornamental design for a display screen or portion thereof with animated graphical user interface, as shown and described.

DESCRIPTION

FIG. 1 is a front view of a first image in a sequence for a display screen or portion thereof with animated graphical user interface, showing our new design; FIG. 2 shows the second image thereof; FIG. 3 shows the third image thereof; FIG. 4 shows the fourth image thereof; FIG. 5 shows the fifth image thereof; FIG. 6 shows a sixth image thereof; and, FIG. 7 shows a seventh image thereof.

The appearance of the animated graphical user interface sequentially transitions between the images shown in FIGS. 1 to 7. The process or period in which one image transitions to another forms no part of the claimed design. The broken line perimeter showing the device hardware is provided for the purpose of illustrating environmental structure; whereas all other broken lines illustrate features of the animated graphical user interface. No subject matter depicted in broken lines form part of the claimed design.
